UNITED STATES PATENT OFFICE.

WILLIAM OSTERMEYER, OF ST. LOUIS, MISSOURI.

LIFE-PRESERVING GARMENT.

SPECIFICATION forming part of Letters Patent No. 665,260, dated January 1, 1901.

Application filed January 30, 1900. Serial No. 3,288. (No model.)

To all whom it may concern:

Be it known that I, WILLIAM OSTERMEYER, a citizen of the United States, residing at the city of St. Louis, in the State of Missouri, 5 have invented certain new and useful Improvements in Life-Preserving Waists, of which the following is a full, clear, and exact description, reference being had to the accompanying drawings, forming part of this 10 specification.

My invention relates to a life-preserving waist designed to be worn under the clothing by a person during a voyage or travel on water, the device being of light weight and being 15 so constructed that normally it may lie compactly to the wearer's body, whereas when there is need for the use of the waist the distensible bulbs contained thereby may be distended by forcing air thereinto to render the 20 waist buoyant to an extent that will enable it to sustain the weight of the wearer and prevent the wearer from sinking in the water.

My invention consists in features of novelty hereinafter fully described and claimed.

Figure I is a front perspective view of my life-preserving waist. Fig. II is an exterior view of the waist in open position. Fig. III is an enlarged detail view of one of the lower front corners of the waist with the facing 25 thereof shown partly broken away and showing one of the distensible bulbs and connecting-tubes located therein. Fig. IV is an enlarged sectional view taken on the line IV-IV, Fig. II. Fig. V is a perspective view of 30 one of the T-couplings by which the distensible bulbs and air-conducting tubes are joined. Fig. VI is a perspective view of one of the mouthpieces applied to the air-conveying tubes.

The body of the waist is composed of two sections 1, similar to a corset, joined by elastic- 35 web strips 2 at the back of the waist, each section being provided with an armhole 3 and having shoulder-straps 4. The front 40 edges of these sections are equipped with hooks and eyes 5 and 6. At the lower edge of the waist is a series of loops 7, that receive a belt 8, by which the waist may be securely strapped to the wearer's body at the waist to prevent 45 it from creeping upwardly on the body in the sustaining action of the waist. The sections 1 are each composed of separated facings 1^a,

of cloth, rubber, or other suitable material, providing four individual pockets 9 between the two facings, (see Fig. IV,) two chambers 55 being located in each section. At the lower edge of each section is a reinforcing-facing 10, that is stitched to the section to strengthen it at the edge mentioned. Within the lower edge of each section are pockets 11. 60

12 designates bulbs located in the pockets 9, between the facings 1 and 1^a, in which there is sufficient space to permit the bulbs to be distended to their greatest extent. The bulbs 12 may be of rubber, bladder, or other 65 desirable impervious material that will retain air and is waterproof. Located in the pockets 11 are air-conducting tubes 13. These tubes are joined to the bulbs 12 by T-couplings 14, one of which is shown in detail in Fig. V. 70 The air-conducting tubes 13 are connected together in common and lead to the series of distensible bulbs 12, so that the conveyance of air may be accomplished to all of the bulbs in like manner and uniformly. The air-con- 75 ducting tubes 13 lead upwardly through the waist-sections at the front edges of each section, as seen in Fig. I, and at their ends are provided with mouthpieces 15, containing 80 suitable check-valves.

When the wearer has occasion for the use of the life-preserving waist, as in a shipwreck at sea, all that is necessary for the wearer to do is to place the mouthpieces 15 in his mouth and by blowing therethrough the series of 85 distensible bulbs are distended within the individual pockets 9, the check-valves within the mouthpieces retaining the air from exit from the conducting tubes. When the air-receiving bulbs have been inflated, the waist 90 is in condition for use as a life-preserved and will effectually sustain the weight of the wearer while in the water.

16 designates a clip secured to one of the mouthpieces and provided with a pair of 95 clamping-jaws 17, adapted to receive the other mouthpiece, thereby holding the two mouth- pieces in close proximity to each other, so that they may be upheld together and be conveniently arranged and located for insertion 100 into the mouth.

A life-preserving waist constructed in accordance with my invention is of very light and compact form and may be worn by the

wearer throughout a voyage without inconvenience or discomfort and being upon the wearer's body is always ready for immediate use upon the simple operation of inflating and 5 distending the bulbs therein.

I claim as my invention—

A life-preserving waist comprising two sections, elastic-web strips whereby the sections are joined together at the back, fastenings 10 for joining the sections together at the front, each section being constructed with separated facings, individual bulb-pockets, a shoulder-strap providing an armhole, and a horizontal

pocket and series of loops at the lower edge of the section, the distensible bulbs located 15 in the individual bulb-pockets, an air-conducting tube located in the horizontal pocket, and extending up at the front edge of the sections, and T-couplings connecting the air-conducting tubes with the distensible bulbs, 20 and a valved mouthpiece connected with the air-conducting tube.

WILLIAM OSTERMEYER.
